UNITED STATES PATENT OFFICE.

ARTHUR J. BAZELEY, OF CLEVELAND, OHIO, ASSIGNOR TO THE NATIONAL MALLEABLE CASTINGS COMPANY, OF CLEVELAND, OHIO.

CAR-COUPING.

1,144,317.

Specification of Letters Patent. Patented June 22, 1915.

Application filed February 5, 1913, Serial No. 746,257. Renewed May 20, 1915. Serial No. 29,434.

To all whom it may concern:

Be it known that I, ARTHUR J. BAZELEY, a citizen of the United States, residing at Cleveland, Cuyahoga county, Ohio, have invented new and useful Improvements in Car-Couplers, of which the following is a specification, reference being had to the accompanying drawings, in which—

Figure 1 is a plan of a coupler showing the application of my improvements thereto; Fig. 2 is an elevation thereof, and Fig. 3 is a section on line III—III of Fig. 1; Figs. 4 and 5 are details of the coupler knuckle and one of the coupler ears respectively.

My invention relates to car couplers and consists in providing vertically extending projections on the knuckle adjacent to the hub, which on one side provide bearings against the outer faces of the coupler ears and on the other form part of the contour of the inner face of the knuckle, so that in buffing the nose of the opposing coupler will strike the said bearing instead of the coupler ears and the force of the buffing blow will thus be utilized to the fullest extent throughout the closing movement of the knuckle up to the moment when the lock drops and the knuckle is locked, and so that the pivot pin may be relieved of strain.

When opposing couplers of ordinary construction come together on a straight track there is ordinarily no difficulty about coupling, but when the couplers approach each other at an angle—as in coupling on a curve—there is frequently great difficulty in making them couple, and coupling is achieved only after a number of attempts in which the cars are brought together with considerable force and with resulting detriment to the equipment. In such instances the trouble in coupling is usually due to the fact that the knuckle of the opposing coupler strikes the guard arm of the coupler and is thereby driven transversely by the incline of the guard arm so that the nose of the opposing coupler will jam against the coupler ears, which are relatively immovable, and the impulse imparted to the knuckle by the opposing coupler is lost toward the end of the closing movement. This difficulty is obviated by my improved construction, which permits the knuckles of opposing couplers to come together with-

out the impact of the buffing blow being taken up by the coupler ears before the knuckle or knuckles have reached locking position.

Referring to the drawings (in which I have shown a coupler of the type described and claimed in my co-pending application, Serial No. 736,889, filed December 16, 1912), A indicates the coupler-head, B the knuckle and C the knuckle-pin. The knuckle B has vertically-extending projections 2 on the forward side of the knuckle hub 3. The projections 2 have continuous bearings 4 under buffing stresses against the ears 5 of the coupler-head, and these bearings are carried clear around to the rear of the pivot pin to the point 6 and extend tangentially thereto from the coupler ears and are engaged by corresponding vertically-disposed bearings 7 on the coupler ears 5. The projections 2 at the point 8 form part of the continuous bearing wall 9 on the knuckle adjacent the hub 3 by reason of the fact that the coupler ears 5 have been cut away and are of smaller diameter than is the case with the ordinary coupler. The cutting away of the coupler ears 5 has been found feasible by reason of the fact that in this form of coupler the knuckle is designed to transmit buffing and draft stresses directly to the coupler-head, and the coupler-ears and the pivot-pin may accordingly be weakened without detriment to the coupler. It will thus be seen that in buffing, as the nose 10 of the opposing coupler strikes the continuous wall 9 of the knuckle B at or near the point 8, it will have a rolling action upon the knuckle at this point and will drive it into closed position in such manner that the impulse given the knuckle B will continue until the lock drops into closed position. A further advantage with this form of coupler is that the knuckle B will have a continuous socket bearing against the ears 5 of the coupler.

It is obvious that my improvement may be applied to various types of couplers and that various changes may be made in the form and arrangement of the parts without departing from my invention, since

What I claim is:

In a car coupler, a coupler knuckle having continuous vertically extending projections bearing against the outer faces of the coupler ears, and forming part of the contour of the

inner face of the knuckle and extending from the outer side of said ears around the inner side of said ears and tangentially to the curved faces of said ears to the rear of the hub of the knuckle, the said bearing being adapted to coöperate with the said ears, and with shoulders on the coupler head ex- tending rearwardly therefrom to relieve the pivot pin from lateral pressure.

ARTHUR J. BAZELEY.
